UNITED STATES PATENT OFFICE.

HERBERT SANFORD MALTBY, OF SANTA CRUZ, CALIFORNIA.

DESIGN FOR A LAMP-CHIMNEY.

SPECIFICATION forming part of Design No. 24,858, dated November 5, 1895.

Application filed September 20, 1895. Serial No. 563,144. Term of patent 14 years.

To all whom it may concern:

Be it known that I, HERBERT SANFORD MALTBY, a citizen of the United States, residing at Santa Cruz, county of Santa Cruz, State of California, have invented and produced a new and original Design for Lamp-Chimneys, of which the following is a specification, reference being had to the accompanying drawings, in which the figure is a perspective view of my lamp-chimney, illustrating my design.

The leading feature of my design consists in a lamp-chimney of conventional form, having a circumferential flange A projecting from

its lower straight portion and broken at intervals to leave intervening spaces, said flange having an essentially-triangular or V shape in cross-section, its upper side being substantially horizontal.

What I claim is—

The design for a lamp chimney as shown and described.

In witness whereof I have hereunto set my hand.

HERBERT SANFORD MALTBY.

Witnesses:

O. J. LINCOLN,

G. C. PRATCHNER.
